CLAIM

The ornamental design for a picture frame package, as shown and described.

DESCRIPTION

FIG. 1 is a front perspective view of a picture frame package showing our new design.

FIG. 2 is a top view thereof.

FIG. 3 is a right side view thereof.

FIG. 4 is a front view thereof.

FIG. 5 is a left side view thereof.

FIG. 6 is a bottom view thereof.

FIG. 7 is a rear view thereof.

FIG. 8 is a front perspective view of a double-corner, folded-edge picture frame package showing my new design.

FIG. 9 is a top view thereof.

FIG. 10 is a right side view thereof.

FIG. 11 is a front view thereof.

FIG. 12 is a left side view thereof.

FIG. 13 is a bottom view thereof.

FIG. 14 is a rear view thereof.

FIG. 15 is a front perspective view of a single-corner, unfolded-edge picture frame package showing my new design.

FIG. 16 is a top view thereof.

FIG. 17 is a right side view thereof.

FIG. 18 is a front view thereof.

FIG. 19 is a left side view thereof.

FIG. 20 is a bottom view thereof; and,

FIG. 21 is a rear view thereof.
